(57) **CLAIM**

The ornamental design for an adaptor for securing a bag to a breast pump, as shown and described.

DESCRIPTION

FIG. 1 is a top, front, and right side perspective view of an adaptor for securing a bag to a breast pump, illustrating the adaptor secured to a breast pump;

FIG. 2 is a top, front, and right side perspective view of the adaptor for securing a bag to a breast pump;

FIG. 3 is a front view thereof;

FIG. 4 is a right side view thereof;

FIG. 5 is a top view thereof;

FIG. 6 is a rear view thereof;

FIG. 7 is a left side view thereof; and,

FIG. 8 is a bottom view thereof.

The broken line showing the breast pump in FIG. 1 illustrates environment and forms no part of the claimed design. All other broken lines illustrate portions of the adaptor for securing a bag to a breast pump that form no part of the claimed design.

1 Claim, 8 Drawing Sheets
